UNITED STATES PATENT OFFICE

149,627

DESIGN FOR A WALL DESK

Erling G. Fossum and Stanley J. Zielinski, Chicago, Ill., assignors to Stewart-Warner Corporation, Chicago, Ill., a corporation of Virginia

Application August 23, 1946, Serial No. 132,765

Term of patent 14 years

(Cl. D33—7)

To all whom it may concern:

Be it known that we, Erling G. Fossum and Stanley J. Zielinski, citizens of the United States, residing at Chicago, in the county of Cook and State of Illinois, have invented a new, original, and ornamental Design for Wall Desk, of which the following is a specification, reference being had to the accompanying drawing, forming part thereof.

Fig. 1 is a perspective view of a wall desk, embodying my new design, showing the table element in an elevated position; and

Fig. 2 is a perspective view similar to Fig. 1 but with the table element in its lowered position.

The rear of the desk is plain.

We claim:

The ornamental design for a wall desk, substantially as shown and described.

ERLING G. FOSSUM.
STANLEY J. ZIELINSKI.
